UNITED STATES PATENT OFFICE.

FRANK S. SNYDER, OF POUGHKEEPSIE, NEW YORK, ASSIGNOR TO THE DE LAVAL SEPARATOR COMPANY, OF NEW YORK, N. Y., A CORPORATION OF NEW JERSEY.

RING INSERTER FOR MILKING-MACHINE TEAT CUPS.

1,408,039.

Specification of Letters Patent. Patented Feb. 28, 1922.

Application filed January 4, 1921. Serial No. 434,868.

To all whom it may concern:

Be it known that I, FRANK S. SNYDER, a citizen of the United States, residing at Poughkeepsie, county of Dutchess, and State 5 of New York, have invented a new and useful Improvement in Ring Inserters for Milking-Machine Teat Cups, of which the following is a full, clear, and exact description, reference being had to the accompanying drawings, which form a part 10 of this specification.

The object of my invention is to provide means for inserting expanding rings into elastic tubes. The invention, while applicable to other analogous uses, is particularly adapted for the insertion of the metallic ring that is used to expand a part of the flexible liner in certain types of teat cups for milking machines.

20 United States Patent No. 1,363,522, dated December 28, 1920, to Meredith Leitch, shows a ring inserter which is efficient except that removal of the rubber tube with the inserted ring from the ring supporter is 25 difficult.

The object of my invention is to provide means that will effectually support the ring while the tube is being stretched over it and yet will be readily removable from the portion of the tube contracted below the ring.

30 In the drawings, which show a ring inserter embodying my invention in a preferred form:

Fig. 1 is a plan view of one member of 35 the ring inserter.

Fig. 2 is a side view of the same member.

Fig. 3 is a side view of the other member.

Fig. 4 is a side view of both members 40 of the inserter, in connection with a flexible tube (in cross-section) showing the parts in the positions they assume during the first step of the process of inserting a ring into the tube.

Fig. 5 is a view, similar to Fig. 4, showing 45 the relation of the parts during the second step.

Fig. 6 is a view, similar to Figs. 4 and 5, showing the relation of parts during the third step.

50 Fig. 7 shows a tube with the ring in place.

a is a plate having several elastic fingers *b* upstanding therefrom in a frusto-conical relation. *c* is an enlarged base for a pedestal *d* longer than the fingers *b* and of a

diameter not greatly different from the inside diameter of the tube in which the ring is to be inserted. Pivoted in the top of the pedestal *d* are three fingers *e* having their upper portions of a length to fit inside the ring to be inserted and their lower portions of a greater length to form a support for the ring. *f* is one of the rings to be inserted and *g* a rubber tube.

60 In operating the device to insert the ring into the tube, one of the rings *f* is placed around the upper portions and rests on the longer lower portions of the fingers *e*. The fingers *b* are then squeezed together at the top and one of the rubber tubes is slipped 65 a short distance over them. The plate *a* and fingers *b* are then forced down around the ring *f* supported by the fingers *e* on the pedestal *d* and carry the tube down to the position shown in Fig. 5. The tube and 70 ring are now lifted off, the fingers *e* turning up as shown in Fig. 6 permit this to be accomplished easily. As soon as the bottom of the tube *g* is above the fingers *e*, it assumes the form shown in Fig. 7. The 75 plate *a* and fingers *b* may now be easily removed ready for the next tube and ring.

Having now fully described my invention, what I claim and desire to protect by Letters Patent is:

85 1. A device for inserting a ring into an elastic tube comprising, in combination, means to stretch the tube, and a ring support adapted to pass the ring through the stretching means into the tube, said support being arranged to permit the stretcher to collapse after the ring has passed the stretcher.

90 2. A device for inserting a ring into an elastic tube, comprising, in combination, means to stretch the tube, and a ring support adapted to pass the ring through the stretching means into the tube, said support being collapsible to permit free removal of the tube with inserted ring.

95 3. In a device for carrying a rigid ring through a tube stretching device into a tube, in combination, means adapted to assume an extended position to support the ring or a retracted position to prevent resistance to removal of the tube.

100 4. In a device for carrying a rigid ring through a tube stretching device into a tube, in combination, a pedestal and a plurality of normally radial ring supporting fingers

110

adapted to assume positions parallel to the axis of the pedestal during the removal of the tube with its inserted ring.

5. A device for inserting a ring into an elastic tube, comprising a ring supporting and ring inserting member, a tube-stretching member adapted to be inserted into the end of the tube and to be moved, with the tube, telescopically relatively to the first member and in such movement to be expanded to permit the entrance of the ring within the tube, and means to contract the diameter of the ring inserter to facilitate the disengagement of the tube and its inserted ring.

6. In a device for inserting a ring into an elastic tube, the combination with means to stretch the tube of means to pass the ring through the stretching means into the tube, comprising a pedestal of a diameter less than the ring and, supported thereby, fingers adapted in one position to support a ring and in another position to permit free removal of a tube contracted below the ring.

25 7. A device for inserting a ring into an elastic tube, comprising means to enlarge the

diameter of the tube, a pedestal adapted to be inserted into the tube through said stretching means, fingers pivotally carried by the pedestal and adapted to extend radially thereof in one position and longitudinally thereof in another position, said fingers affording a ring support in their radial extension and releasing the ring in their longitudinal extension.

30 8. A device for inserting a ring into an elastic tube, comprising a tube stretching member, a pedestal adapted to be inserted into the tube through said stretching member, a plurality of fingers, having end shoulders, pivotally secured to said pedestal, said fingers affording a support for a ring in the operation of inserting the ring and turning on their pivots in the operation of withdrawing the pedestal; thereby releasing the ring and permitting the free withdrawal of the pedestal from the tube.

35 In testimony of which invention, I have hereunto set my hand, at Poughkeepsie, N. Y., on this 28th day of December, 1920.

50

FRANK S. SNYDER.
